UNITED STATES PATENT OFFICE.

BARTON A. PROCTOR, OF BRIDGETON, NEW JERSEY, ASSIGNOR TO KINOIKON APPARATUS CORPORATION, OF BRIDGETON, NEW JERSEY, A CORPORATION OF DELAWARE.

PROTECTIVE SHIELD AND FIRE-SHUTTER.

1,298,392.

Specification of Letters Patent. Patented Mar. 25, 1919.

Application filed June 21, 1917. Serial No. 176,051.

To all whom it may concern:

Be it known that I, BARTON A. PROCTOR, a citizen of the United States, residing at Bridgeton, Cumberland county, State of New Jersey, have invented certain new and useful Improvements in Protective Shields and Fire-Shutters for Moving-Picture Projectors, of which the following is a specification.

My invention relates to moving picture projectors and more particularly to such projectors as are employed to project or display pictures arranged successively upon a length or reel of film, as is now common in the art.

More particularly my invention relates to a shield or door for closing the housing, containing the film display mechanism and that part of the film lying in the path of the projected beam of light, and to a drop or fire shutter combined with said door in such a way that, when the film is being displayed, the housing will be closed but the shutter open while, when it is necessary to have access to the display mechanism for any purpose, the door may be opened so as to completely intercept the projected beam and shield the film against the heat rays constituting a part of said beam.

The object of my invention is to provide a door or shield combined with a drop or fire shutter for the purpose specified, of simple construction, unlikely to get out of order, and capable of instantly being so disposed as to afford access to the display mechanism while at the same time completely cutting off the beam of projected light and preventing any impingement thereof upon the film.

In moving picture projectors as now used, the beam of projected light is ordinarily of such intensity that, unless the film be moved across said beam at a suitable rather high rate of speed, the heat absorbed by such film will be sufficiently great to ignite the film, if of inflammable material as it commonly is. As such films not only burn readily but almost explosively, the danger not only to the apparatus but also to other property, as well as to human life, is very great.

It is often necessary, during the operation of a projector, to open the machine and make some adjustment of the film or of the display mechanism. While various devices have been proposed whereby a fire shutter

is dropped across the path of the projected beam when the display mechanism stops or runs at less than a certain determined speed, such arrangements do not contemplate screening the film from the projected beam when the housing is opened and it is therefore necessary, in order to protect the film, to extinguish the lantern or, at any rate, to lessen its intensity of illumination. This, however, is a disadvantage not only because it taxes the operator's time and attention but inasmuch as the display mechanism is then likely to be insufficiently illuminated for the purpose of making the necessary and desired adjustment.

Briefly described, my invention comprises a door or shield which covers or closes that side of the display mechanism housing which is immediately adjacent the projecting lens. In this shield I provide an opening adapted to be closed by a suitable drop shutter attached to the door. The door is arranged slidably (and normally to its plane) with respect to the housing and a movable pin is so mounted in the housing that it is adapted to be thrown out or in by an operative part of the display mechanism according as the film is running above or below (or is stationary) a certain critical rate of speed. When the housing is closed by the door, the fire shutter is so located with respect to this pin that it will be opened by the thrust out pin abutting against it so as to permit the film to be projected whenever the display mechanism is running at more than the determined speed. If for any reason, and whether the film be running or not, it is desired to get at the display mechanism for purposes of adjustment or otherwise, the door is slid away from the housing thereby carrying the drop shutter away from the pin by means of which it has been or could be held in open position. The drop shutter will therefore either close at once or remain closed as the case may be, and, since the door is moved away from the housing along a line normal to itself, the projected beam will at all times be intercepted and the film protected.

My invention will be better understood by referring to the accompanying drawings in which Figure 1 represents an elevation, partly in section, showing as much of a moving picture projector as is necessary to an understanding of the invention, my im-

proved protective shield being shown in closed position (dotted lines show the open position of the shield); Fig. 2 is a view similar to Fig. 1 but taken from the other side 5 of the projector, the protective shield being shown in open position; and Fig. 3 is a plan view, taken along the line 3—3 of Fig. 2.

In the drawings, a base or platform 1, 10 adapted to be pivotally mounted upon a suitable pedestal (not shown) so as to be adjustable about a transverse axis, carries the fixedly attached housing 2 for the film display mechanism, this housing being provided above and below, respectively, with a 15 film feed reel casing 3 and a take-up reel casing 4.

Sprocket wheels 5, 6 and 7 are driven by suitable mechanism (not shown) in the usual 20 way so as to carry film 8 across the beam of light projected through lenses 9 and 10.

Housing 2 is provided on its rear side, 25 adjacent to lens 9 which is directly attached to the lantern, with a door 11 carrying a slide bar 12 mounted in slide way 13 formed upon one side of the housing 2. This slide way comprises a pair of parallel bars 14, 15 fixed against the side of the housing and covered by a plate 16 provided with a longitudinal slot with which is engaged a pin 17 30 fixed in the slide bar 12.

Door 11 may hence be slid in and out in a direction normal to its plane so as to either close the housing 2 or completely open the 35 same. A handle 18 is provided for convenience in thus slidably moving the door.

The door is provided with a rectangular opening 19, the upper edge of this opening carrying a spindle to which is affixed a fire 40 shutter 20 and a pinion 21.

Slidably held in the door 11 with its teeth meshed with pinion 21 is a short rack rod 22 at the outer end of which is a transverse push bar 23. Slidably mounted in the housing 45 2 is a pin 24 adapted to be projected outwardly or inwardly with respect to the housing according as the film display mechanism is operating at a greater or less rate of speed. This is accomplished by providing an operative connection between pin 24 and some movable part of the film display mechanism but this connection is not shown or described herein as not being essential to the invention. It is, however, shown and described 50 in my companion application, Serial No. 176,052, filed June 21, 1917.

The pin 24 is so located in the housing that when the door 11 is closed the end of the pin is in a line which, projected, will 55 intersect the push bar 23.

The lower half of the door 11 is hinged at 25 and provided with an undercut lug 26 so positioned that, when this lower part of the door is raised, a hook formed at one end 60 of a gravity catch 27 pivotally attached to

the upper half of the door, will engage the undercut end of lug 26 and hold the lower half of the door in elevated position.

The operation of my invention is as follows: When the door is closed and the display mechanism is not running, or is running at less than the critical speed, pin 24 will be in retracted position and out of contact with push bar 23. The drop shutter 20 will therefore remain closed by its own 75 weight. If, however, the display mechanism is run at a speed greater than the critical speed, pin 24 will be projected from the housing so as to abut and push against push bar 23, thereby pushing rack rod 22 outwardly and rotating pinion 21 so as to raise the drop shutter.

If at any time, whether the display mechanism is running or not, it is desired to gain access to the film display mechanism the 85 knob or handle 18 is grasped and the door 11 pulled away from the housing. This immediately interrupts the coöperative relation between rack rod 22 and pin 24 and permits the drop shutter to fall and close 90 the door opening. The projected beam of light from the lantern is therefore intercepted at such times.

Variations of detail will occur to those skilled in the art and are within the scope 95 and spirit of the following claims.

1. In a moving picture projector, a housing for the film display mechanism, a door for closing the rear side of the housing arranged to slide in a direction normal to its 100 surface and provided with an opening, a shutter for said opening, and a pin movably mounted in the housing and adapted to co-operate with the shutter when the door is closed the position of the pin determining 105 the position of the shutter, whether open or closed, and being itself determined by the rate of speed of the film display mechanism.

2. In a moving picture projector, a housing for the film display mechanism, a door for closing the rear side of the housing arranged to slide in a direction normal to its surface and provided with an opening, a shutter hinged at the upper edge of the opening, and a movable member mounted in the housing 110 and in coöperative relation with the shutter when the door is closed so that when the movable member is in one position the shutter will be opened and when it is in another position the shutter will be permitted to 115 close.

3. In a moving picture projector, a housing for the film display mechanism, a door for closing the rear side of the housing arranged to slide in a direction normal to its 125 surface and provided with an opening, a shutter hinged at the upper edge of the opening, a pinion fixed to and moving with the shutter, a rack slidably in the door and meshing with the pinion, and a pin mounted 130

movably in the housing and abutting against the rack so that the position of the pin determines the position of the rack and hence of the shutter.

- 5 4. In a moving picture projector, a housing for the film display mechanism provided with an opening on the side adjacent the condenser, a door arranged to slide in a direction normal to its surface for closing said 10 housing opening and provided with a second opening, a shutter for said second opening, and a movable member mounted in the housing and in coöperative relation with the shutter when the door is closed the position 15 of the movable member determining the position of the shutter, whether open or closed.
5. In a moving picture projector, a housing for the film display mechanism provided

with an opening on the side adjacent the condenser, a door for closing said housing 20 opening said door being arranged to remain in the path of the projected beam whether open or closed and being provided with a second opening, a shutter for said second opening, and a movable member supported 25 by the housing and in coöperative relation with the shutter when the door is closed but disconnected therefrom when the door is open, the position of the movable member being controlled by the rate of speed of the 30 film mechanism and itself determining the position of the shutter whether open or closed.

In testimony whereof I have hereunto set my hand.

BARTON A. PROCTOR.
